CLAIM

(52) **U.S. Cl.** **D14/409**

The ornamental design for a mouse user interface with configurable components, as shown and described.

(58) **Field of Classification Search**

DESCRIPTION

USPC D14/402-411, 356, 388, 389, 383-385,
D14/417, 426; 345/156-167; 463/36-38;
358/471, 473; 273/148 B

FIG. 1 is a first top perspective view of a mouse user interface with configurable components;

See application file for complete search history.
